(57) **CLAIM**

The ornamental design for a vehicle running board, as shown and described.

DESCRIPTION

FIG. 1 is a front, top and left side perspective view of a vehicle running board showing our new design;

FIG. 2 is a rear, bottom and left side perspective view thereof;

FIG. 3 is a front view thereof;

FIG. 4 is a rear view thereof;

FIG. 5 is a top plan view thereof;

FIG. 6 is a bottom plan thereof;

FIG. 7 is a left side view thereof;

FIG. 8 is an enlarged cross-sectional view taken along line 8-8 in FIG. 3;

FIG. 9 is an enlarged cross-sectional view taken along line 9-9 in FIG. 3;

FIG. 10 is a front, top and left side perspective view with the board being folded; and,

FIG. 11 is a rear, bottom and left side perspective view with the board being folded.

The broken lines illustrate portions of the vehicle running board that form no part of the claimed design. The dash-dotted lines denote the boundary of the claim and form no part of the claimed design.

1 Claim, 11 Drawing Sheets
